OUTBOARD MOTOR

Warren C. Conover, Waukegan, Ill., assignor to
Outboard Marine & Manufacturing Company,
Waukegan, Ill., a corporation of Delaware

Application June 6, 1938, Serial No. 212,078

10 Claims. (Cl. 115—18)

This invention relates to improvements in outboard motors.

An important object of the invention is to provide a novel and improved organization of passages for the flow of fluids through the device. More particularly stated, it is an object of the invention to provide an outboard motor organization freely rotatable on its swivel bearing for steering and yet provided with an under water exhaust. This involves as an objective the delivery of exhaust gases through the shaft housing in immediate proximity to the crank case, and this in turn makes it desirable, and it is a further objective of the present invention, to provide means for cooling the gases and particularly for keeping the engine crank case cool under circumstances which, but for a very novel organization of the cooling system, might in this particular arrangement of the exhaust gas passages, result in overheating the crank case and the lubricant and combustible mixture therein contained.

Also involved in the objects of the invention is the provision of a novel engine structure closely related to the problems aforesaid in that I desire to provide special crank case, engine bearing, cooling jacket, exhaust manifold, intake passage, water connection, shroud, and other features of facilitating the flow of gases and water in an outboard motor structure organized to provide an under water exhaust and yet to permit of free swiveling movement for steering and reverse.

Other objects of the invention relate to a novel and improved construction of the drive shaft casting and supplemental shaft housing, likewise specifically developed for the aforesaid purposes. Still other objects of the invention relate to a novel improved construction of lower unit and the water circulating pump and passages therein contained, as well as to a specifically improved driving connection to the propeller shaft therein.

Other objects will appear in more detail from the following disclosure.

45 In the drawings:

Figure 1 is a side elevation of a complete outboard motor embodying the invention.

Figure 2 is an enlarged detail view of the upper part of the motor in vertical fore and aft section.

50 Figure 3 is a view of the lower part of the motor on an enlarged scale in axial fore and aft section.

Figure 4 is a fragmentary detail view taken in section generally on the line 4—4 of Figure 2, the 55 so-called shaft housing flange being exposed in

plan and partially broken away to show the underlying structure in section.

Figure 5 is a detail view taken in section on the line 5—5 of Figure 4.

Figure 6 is a view taken in section on the line 5—6 of Figure 4.

Figure 7 is a view taken in section on the line 7—7 of Figure 2.

Figure 8 is a view taken in horizontal section through the upper part of the fuel tank and the cylinder-enclosing shroud, portions of the flywheel being broken away to show the underlying engine structure in plan.

Figure 9 is a detail view taken in section on the line 9—9 of Figure 2.

Figure 10 is a detail view in side elevation of the adjustable thrust bushing member shown in Figure 9.

Figures 11, 12, 13, 14, 15 and 16 are views of the engine and its relation to the drive shaft 20 housing and carburetor with particular reference to the fluid passages. Figure 11 is a view taken in section transversely through the engine on the line indicated at 11—11 in Figure 12. Figure 12 shows the engine in side elevation with parts 25 broken away to expose the interior passages. Figure 13 is a view taken in section on the line 13—13 of Figure 14. Figure 14 is a view taken in section on the line 14—14 of Figure 13. Figure 15 is a view taken in section on the line 30 15—15 of Figure 14. Figure 16 is a view in perspective of the separately constructed plate which provides an expansion chamber and inlet manifold for the engine.

Like parts are identified by the same reference 35 characters throughout the several views.

The outboard motor is made to swivel as a unit for steering and reversing in the swivel bearing 20 which, for purposes of illustration, is carried by a bracket arm 21 pivoted at 22 to a more or less conventional transom bracket 23 having spaced arms 24 provided with arcuate slots in which the semi-tubular thrust bearing 25 is adjustable. This bearing is preferably provided with a transverse boss 26 having guide flanges 27 45 fitted to the slots of the respective arms 24 so that in all positions of adjustment of the thrust bearing 25 longitudinally of the arms the bearing will be maintained at the proper angle to receive the drive shaft housing hereinafter to be described.

A clamping bolt 28 extending through the bushing and having its head and wing nut engaged with arms 24, maintains the bushing in adjustment to determine the initial upright po- 55

sition of the outboard motor to which it will return under thrust of its propeller when tilted about the pintle 22, as in encountering a shoal or other obstacle.

5 That portion of the outboard motor structure which is swivelled in bearing 20 is known as the shaft housing. It preferably constitutes a support upon which the power head and lower unit are unitarily assembled. In this instance the 10 shaft housing preferably comprises a composite structure including a casting 30, an outer tube 31, and an inner casing 32. The casting 20 connects the tubes 31 and 32 in the desired assembly, provides the necessary passages for water and 15 exhaust gas hereinafter to be described, serves as a base to which the tiller is connected, and provides a mounting flange upon which the entire power head is carried.

It will be noted that the outer sleeve 31 is 20 pressed into the sleeve-like lower nut of the casting 30. The outer tube and casting 30 together provide a passage 33 for exhaust gases which has an opening laterally at 34 to receive such gases from the power head. Above this opening the 25 inner casing 32 is anchored in a bushing 35, the object of this inner tube being to exclude gases and water from contact with the drive shaft 36, and from the crank case bearings.

The supply water pipe 37 terminates in casting 30, where it is held by an expander 38 as shown in Fig. 5 for delivery of water through the mounting flange 40 of casting 30 toward the power head.

The return water is delivered from the power 35 head through pipe 42 into the short discharge passage 43 formed within the casting 30 and arranged to discharge the partially heated water directly into the exhaust stream.

Supported on the flange 40 (Figs. 2, 4, 5 and 40 12) is the entire power head. This comprises an engine self-contained even to the inclusion 45 of a fuel tank and, preferably, a flywheel magneto. Bolts 44 connecting to the crank case 45, and bolt 46 connecting to the fuel tank 47, and 50 bolts 48 connecting to the exhaust manifold portion 49 of the cylinder casting 50, serve to maintain the power head in assembly on the shaft housing structure.

As indicated in Figs. 7, 12 and 14, the crank 50 case 45 comprises two parts 45a and 45b united on the transverse axial center line. The bushings in which the crank shaft 51 rotates are preferably made as shown in Fig. 7 to comprise two 55 semi-tubular bushing sectors 52 and 53, each of which has an arcuate extent somewhat less than 180 degrees, and each of these sectors being cast into the metal of its associated component part of the crank case. By casting these bushing sectors into the metal of the crank case a portion 60 of the crank case metal flows about the end of each bushing sector, thereby anchoring the sector securely against rotative displacement in the casting. The bushing 54 of the connecting rod bearings of connecting rods 55 may be similarly 65 cast into the component parts of the bearings. The upper end of crank shaft 51 may carry a conventional flywheel magneto 56, and its lower end may be provided with a squared socket to receive the correspondingly formed upper end 70 of the drive shaft 36, this arrangement also being conventional.

The crank case 45 preferably has a central bearing at 58 dividing the crank case into two separate chambers wherein the crank shaft has 75 diametrically offset cranks to which the con-

necting rods 55 connect the pistons 59 for movement in the cylinders 60. The cylinders in this particular style of motor are superimposed and the design is a conventional one in which the firing alternates so that when the engine is operated on the two cycle principle the two cylinders yield two power impulses for each crank shaft revolution. 5

The cylinders 60 comprise an integral part of the cylinder casting 50. This casting also includes a jacket 61 and the means 49 which provides a portion of the exhaust gas passage. The stern side of the crank case and the stern side of the underlying shaft housing casting 30 are machined to a common face at 62 abutted by 15 the complementary face of the cylinder casting.

A series of webs connect the cylinders 60 with the jacket 61 in the cylinder casting 50. Some of these webs partition off the gas passages and will be described later. At this time attention is 20 invited to the web 63 which extends circumferentially about both cylinders as shown in Fig. 2 and Fig. 15 to divide the water jacket space into the base compartment 66 and the head compartment 67. A small hole through this partition web at 68 is intended solely for drainage and does not by-pass any substantial volume of water during engine operation.

The base portion 69 of the crank case has a 25 downwardly opening annular channel at 70 registering with the hole 71 which extends through the supporting flange 40 of the shaft housing adjacent the terminus of the water supply pipe 37 (Figs. 2, 4 and 5). The channel 70 is not only a water conduit but, of itself, it provides 30 a cooling jacket handling water fresh from the lake in which the outboard motor operates and thereby providing a very effective chilling medium between the crank case and that portion of the lower unit casting 30 into which the hot 35 exhaust gases are delivered.

An opening at 73 in the rear face 62 of the crank case registers with an opening 74 in the cylinder casting 50 to afford communication between the channel 70 and the base jacket compartment 66. It is desirable that the base jacket chamber 66 should initially be cooled by the 40 arriving water first, for the protection of the crank case from engine heat, and secondly, because the heat thus initially imparted to the 45 water will enable the combustion chamber desirably to operate at higher temperatures than would otherwise be the case.

Any leakage from channel 70 toward the drive 50 shaft 36 is received in a well 72 (Fig. 6) which 55 is drained by a duct 730 to the outside of casting 30. The upper end of the inner drive shaft casting 32 is socketed in a plug 740 having an upstanding annular flange about the drive shaft 36 60 to serve as a dam for keeping the water from falling along the drive shaft.

From the top of the base jacket compartment 66 I provide an external water pipe 75 (Fig. 15) which leads downwardly and at a rearward inclination to enter the bottom of the jacket compartment 67 by which the heads of the cylinders are enclosed. Thus the water partially heated in the jacket chamber 66 rising naturally toward the top of that chamber, is removed from the 70 top of base chamber 66 and enters at the bottom of chamber 67 through which the water again rises toward the discharge pipe 42 opening from the top of compartment 67 and returning to deliver the overflow water into the exhaust gases 75

through the duct 48 cast in the shaft housing casting 38 as previously described.

The drain opening 68 acts as a partial by-pass for the water supplied to chamber 66. An additional portion of the water supplied to chamber 66 is by-passed through the opening 77 (Figs. 2 and 15) to the jacket compartment 78 which intervenes between the transfer ports 79 and finally opens into the main head jacket compartment 67 after such transfer ports terminate.

Unlike other motors of this type, the intake and exhaust passages are provided at the same side of the cylinder block and are cast in the same piece. An expansion chamber is preferably provided partially within this added piece and partially within a cavity formed in the side of the cylinder block, the exhaust manifold being preferably formed in the cylinder block itself for reasons hereinafter to be stated.

20 The casting 80, which is shown separately in perspective in Fig. 16, is bolted to the cylinder block to provide in conjunction therewith a jacketed expansion chamber 81 and an inlet manifold 82 having a mounting flange at 83 for a carburetor 84. The manifold is subdivided by partition 85 to provide passages leading to the intake ports 86 and 87 of the respective cylinders. This being a three port engine, the ports 86 and 87 are controlled by the skirts of the respective 25 pistons 59 (Fig. 14) to admit the incoming charge to the crank case when the piston is at the top of its compression stroke. During the expansion stroke of the piston the charge is compressed in the crank case and finally delivered to the cylinder through the appropriate transfer port 79 which, on entering the cylinder, is preferably subdivided by bridges in the usual manner as shown in Fig. 11. At the time of transfer the gases burned in the cylinder are discharged through 30 the exhaust ports 90 into the common expansion chamber 81 (Figs. 11, 12 and 14).

As shown in these views, the expansion chamber is partially formed within the cylinder casting and partially within the casting 80, the latter being provided with a water jacket at 91 which communicates with the cylinder jacket space 67 through ports 92 at the bottom and 93 at the top of the horizontal cylinder casting (Fig. 12). As clearly shown in the drawings, the cylinder 45 jacket chamber 67 surrounds the outer ends of the respective cylinders and also cools the expansion chamber 81, the expansion chamber being completely surrounded with water jacketing except adjacent a pipe of the intake manifold.

50 The exhaust manifold 95 is not formed within the expansion chamber casting 80, but is formed as a part of the cylinder block, extending around beneath the lower cylinder and opening into the shaft housing through the exhaust port 34 as 55 previously described. As above noted, a single machined surface at 62 may be continuous across the cylinder casting and the exhaust manifold built therein and in such case may co-act with a single complementary planiform machined surface 60 face on the crank case and lower unit so that gasket means applied between these respective surfaces will seal the crank cases in communication with their respective cylinders and will seal the water supply connection and the exhaust gas 65 connection. In practice there are some advantages in having these surfaces only approximately in the same plane, one of the surfaces at one side or the other being offset perhaps .020 inch, whereby a gasket of slightly increased thickness may 70 be used between the cylinder and the lower unit.

The fuel tank 47 extends arcuately about the crank case, enclosing the forward side thereof and supported centrally on the tiller handle bracket 40. Pivoted to the fuel tank by means of links 97, one of which is shown in Fig. 1, 5 is a shroud 98 enclosing the cylinder portion of the engine and particularly the spark plugs 99. Access to the spark plugs is readily had by dropping the shroud to the position shown in dotted lines in Fig. 1 upon release of the bolt 100 which 10 normally holds the shroud securely to the boss provided at 101 in the cylinder casting (Fig. 2). An opening at 102 in the shroud and an adjoining rounded flange 103 provide a hand hold for facilitating the lifting of the motor in applying 15 it to a boat or removing it therefrom, or for carrying purposes.

The flywheel at 56 may be provided with starting mechanism which, except for the handle 105, is not illustrated, being contained within the 20 cover 106 and having no direct bearing with this invention except insofar as the cover completes the substantial enclosure of the engine which is constituted within the power head of this device.

At the lower unit the outer and inner sleeves 25 31 and 32 constituting the shaft housing are separately anchored. The lower unit casting 110 is provided at its top with a split sleeve clamp 111 tightened by means of bolt 112 on the outer shaft housing sleeve 31 which terminates at the 30 exhaust chamber 113 formed in the casting 110. At the bottom of the exhaust chamber is a socket 114 and a partition wall 115 directing the exhaust gases rearwardly into the discharge pipe 116 which is bolted at the rear of casting 110 and 35 constitutes a rearward extension thereof, the anti-cavitation plate 118 being continuous across the outside of both castings. The discharge mouth 117 for the exhaust gases is located below plate 118 and at the rear of the path of the 40 propeller 120.

The inner casing 32 constituting the shaft housing extends clear across the exhaust chamber 113 and seats in the socket 114 where packing is provided at 121 to prevent the exhaust gases 45 and water from penetrating along the drive shaft 36 into the gear chamber 123. The drive shaft has a bearing in a bushing 124 immediately above the gear chamber. At its end it carries the drive pinion 125 which meshes with a driven gear 50 126 bearing in a bushing 127 provided directly in the lower unit casting 110.

Bolted to the aft surface of the lower unit casting 110 is a casting 130 which provides a closure for the rear side of the gear chamber and also 55 provides a pump casing 132. The propeller shaft 135 has its forward bearing within the driven gear 126 and its rearward bearing in a bushing provided in casting 130 constituting the gear casting closure. Motion is transmitted from the 60 driven gear 126 to the propeller shaft through a torsion spring 136 having one end entering the gear and the other end anchored in the pump cam 137 which is keyed to the shaft. The torsion spring 136 is wound about the portion of 65 the shaft intervening between the gear and the cam and provides a resiliently flexible driving connection calculated to absorb some of the shock to which the propeller may be subject. A shear pin 138 passing through the shaft is engaged in a notch in the hub of propeller 120, the hub being housed to the pin by the nut 139 screwed to the end of the shaft.

The pump comprises a cam follower 140 which is provided with an extension bearing sleeve 141 75

to constitute a displacement piston operating within a cylinder which includes the bushing 142. Adjacent the cylinder the casting 132 receives a cage 143 for a check valve 145 and a hardened seat 146 screwed into the cage and replaceable as required.

The water inlet provided by the cage communicates through the cylinder head 148 with the cylinder bushing 142 and with the replaceable 10 tubular outlet valve seat member 149. On each displacement stroke of the piston against the compression of spring 150, water is forced through the outlet valve 151 and fitting 152 into the water supply pipe 37 which extends upwardly 15 through the shaft housing between the inner and outer tubes thereof in the manner already described. Because of the presence of the inner tube no vibration can bring the supply pipe 37 into frictional contact with the rotating drive 20 shaft 36.

In addition to the protection provided by the spring 136 and shear pin 138 against injury due to the propeller shock, I have mounted the entire outboard motor to tilt upon the bracket pintle 25 whenever the skeg 155 strikes a shoal or obstacle. The thrust bearing sleeve 156 carried by the intermediate portion of the shaft housing can move freely away from the semi-tubular thrust bearing pad 25 of the bracket as long 30 as the motor is being operated in a forward direction. Because the reversal of the motor will cause its thrust to be directed rearwardly and therefore will cause bodily oscillation thereof about the pintle 22, a reverse lock comprising 35 a fitting 157 carrying a semi-tubular flange 158 is clamped to the shaft housing in a position such that when the motor is turned bodily in the swivelled bearing 20, as for reversal, the flange 158 will engage behind the thrust bearing pad 40 25 to interlock the parts against tilting. Since the rearward thrust of the propeller is on such occasions exerted entirely through the lower extremity of the pad 25, the key 27 integrally carried by the pad as above described, is of value 45 in preventing the pad from tilting about its clamp screw 28 during reversal.

Those skilled in the art will find in the device herein disclosed a unitary design in which the structures and purposes of all parts have been 50 integrated. Many features which have heretofore been aggregated in existing motors have here been modified to take into account the presence of each other. In the foregoing description I have attempted to point out how the provision 55 of under water exhaust in a fully reversible swivelled motor has led to changes in the construction of the engine, the lower unit, and the cooling and exhaust systems. In fact the outboard motor is a new organization throughout in order 60 to correlate my objectives in a single unitary combination.

I claim:

1. In a device of the character described, the combination with a shaft housing and an engine 65 crank case connected therewith, said shaft housing providing an exhaust passage with a laterally opening port and said crank case and shaft housing having an approximately planiform surface through which said port opens, of a cylinder 70 connected with said crank case at said surface and provided with an exhaust passage portion connected with said shaft housing at said surface, said cylinder overlapping the connection between the crank case and shaft housing.

2. In an outboard motor, the combination with

a drive shaft, of a shaft housing comprising inner and outer casings in spaced relation, and terminal means connecting said inner and outer casings unitarily together, the space between said casings constituting an exhaust passage for which 5 said terminal means provide inlet and discharge ports, the outer casing terminating short of said ports and the inner casing projecting beyond said ports at both of said terminal means.

3. In a device of the character described, the 10 combination with a shaft housing comprising a terminal casting having a tiller connection, of a power head mounted on said casting and comprising an engine having its crank case in connection with said casting, and a cylinder block 15 projecting laterally from said crank case, a fuel tank encircling that side of said crank case remote from said cylinder block, and a shroud for said cylinder casting enclosing said casting and having its side walls constituting rearward extensions of the side surfaces of said fuel tank.

4. In a device of the character described, the combination with a block having bores providing a plurality of cylinders and having exhaust ports opening laterally from said cylinders, of means projecting from the ported side of the block to constitute a seat to provide a recess with which said ports communicate, and a closure detachably connected with said seat and having a recess complementary to that of said 30 block, said closure and block together providing an expansion chamber for receiving the discharge through said exhaust ports, and said block having an exhaust discharge passage opening from said expansion chamber and about 35 which said seat is substantially continuous, whereby exhaust gases are admitted to said chamber and delivered therefrom solely through said block.

5. In a device of the character described, the 40 combination with a cylinder block having a cylinder bore and a port opening laterally therefrom, of seat means projecting laterally from said block and encircling said port, said seat means having an exposed face constituting a seat 45 and surrounding a recess within said seat and means with which said port communicates, said block being provided with an exhaust passage leading from said recess beneath said seat, and a closure having a face complementary to said 50 seat, whereby said closure and block together provide an expansion chamber to which exhaust is delivered through said port and from which exhaust is discharged through the passage in said block.

6. In a device of the character described, the combination with a cylinder block having a cylinder bore and a port opening laterally therefrom, of seat means projecting laterally from said block and encircling said port, said seat 60 means having an exposed face constituting a seat and surrounding a recess within said seat and with which said port communicates, said block being provided with an exhaust passage leading from said recess beneath said seat, and 65 a closure having a face complementary to said seat, whereby said closure and block together provide an expansion chamber to which exhaust is delivered through said port and from which exhaust is discharged through the passage 70 in said block, said block and closure having jackets and being provided with water communication passages extending through said seat and face.

7. A device of the character described, com- 75

prising a cylinder block provided with a plurality of parallel and adjacent cylinder bores and having exhaust ports and intake ports opening from said cylinder bores laterally to the same side of the block, a crank case subdivided to provide separate crank cases corresponding to the respective cylinders and with which the respective intake ports are adapted for communication, pistons reciprocable in the cylinders controlling such communication and controlling exhaust through the exhaust ports, flange means outstanding from said block about said exhaust ports to provide a recess with which said ports communicate, the periphery of said flange means being surfaced to constitute a seat and said block having an exhaust passage communicating with said recess beneath said seat, and a closure for said recess whereby to constitute said recess as an expansion chamber, said closure being internally provided with passages registering with the intake ports of said block and a carburetor mounting flange ported in communication with said passage.

8. In a device of the character described, the combination with an upright crank shaft and a crank case provided with bearings therefor, of pistons in operative connection with said shaft, a cylinder block having cylinder bores in which the pistons are reciprocable, said bores having intake ports communicating with the crank case and exhaust ports on the same side of the cylinder block opening from the respective cylinders, the crank case being subdivided into separate crank case chambers individual to the respective cylinders, means on the side of the cylinder block providing a seat encircling the exhaust ports therein, a chambered closure on said seat constituting an expansion chamber with which said ports communicate, said block containing an exhaust passage leading from said chamber, and charge forming and delivering means connected with said closure and comprising passage means leading to the respective intake ports.

9. In an outboard motor, the combination with a shaft housing provided at its upper end with a closure constituting an engine support, said shaft housing comprising an exhaust passage opening laterally beneath said engine support, 5 of an engine crank case seated on said support, a cylinder block connected with said crank case and with said shaft housing and comprising an integral exhaust passage leading to said support, said cylinder block having laterally opening exhaust port means, and a closure applied laterally to said block about said means and constituting an expansion chamber into which said means communicates and from which said passage leads to said shaft housing. 15

10. In an outboard motor, the combination with a shaft housing comprising an exhaust passage having a lateral inlet opening adjacent its upper end, of an engine crank case connected with said shaft housing, a cylinder block 20 having a cylinder portion connected with the crank case and provided integrally with an exhaust passage formed in said block, said block including a portion through which said exhaust passage extends to said inlet opening, said 25 last mentioned cylinder block portion being connected with said shaft housing whereby said cylinder block is connected across the connection between the crank case and the shaft housing, means on the side of the cylinder block 30 providing a seat and a recess within the seat from which said integral exhaust passage leads, said cylinder block having exhaust port means opening into said recess within said seat in communication with said passage, and a closure applied to said seat and constituting said recess, an expansion chamber adapted to receive gases exhausted from said cylinder block through the exhaust port thereof and to deliver said gases back through the passage of said block into said 35 shaft housing. 40

WARREN C. CONOVER.
